(57) **CLAIM**

We claim the ornamental design for the broom head with two-toned bristles, as shown.

DESCRIPTION

FIG. 1 is a bottom perspective view of a broom head with two-toned bristles showing the new design;

FIG. 2 is a front elevation view thereof;

FIG. 3 is a rear elevation view thereof;

FIG. 4 is a right side elevation view thereof;

FIG. 5 is a left elevation view thereof;

FIG. 6 is a top plan view thereof; and,

FIG. 7 is a bottom plan view thereof.

Specific colors form no part of the claim design, and differences in shading serves merely to represent differences in color.
